(57) **CLAIM**

The ornamental design for an “armrest,” as shown and described.

DESCRIPTION

FIG. 1 is a perspective view of armrest showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a reference view (a perspective view showing a chair with an armrest) thereof.

The broken line showing the remainder of the chair in FIG. 8 is for the purpose of illustrating environmental structure and forms no part of the claimed design.

1 Claim, 8 Drawing Sheets

FIG. 1

FIG. 2

FIG. 3

FIG. 4

FIG. 5

FIG. 6

FIG. 7

FIG. 8
